UNITED STATES PATENT OFFICE

MARTIN FOX, OF CHICAGO, ILLINOIS, ASSIGNOR TO THE SENG COMPANY, OF CHICAGO, ILLINOIS

EXTENSION TABLE

Application filed January 29, 1930. Serial No. 424,395.

My invention is an improvement in tables and more particularly to that type commonly known as refectory tables of the class having extension leaves normally housed under the main top and slideable horizontally and vertically to extended position coplanar with said top.

The principal object of my invention is to provide that special type of extension tables in which the leaves are guided and supported by inwardly projecting bars or runners with simple and effective means which provide for the required movements of the extension leaves and firmly support them in extended position on a horizontal plane with the main top.

With this principal object in view my invention has particular reference to a metal fixture attached to a rail of the supporting frame of the table and having a supporting member cooperating with a pin projecting from the runner and engaging said fixture for holding the leaf extended, said fixture being preferably in the form of a hook to receive the pin when the leaf and runner or runners to which it is attached are slid outwardly and raised vertically to extended position on a line with the main top; all as hereinafter fully described and claimed.

30 In the accompanying drawing:—

Figure 1 is a vertical sectional view through the upper part of an extension refectory table showing the application of my invention, the extension leaves being in housed position. Fig. 2 is an enlarged sectional view of one side of the table with the leaf in extended position.

Fig. 3 is a similar view with the leaf in furthest position for engagement with the supporting fixtures.

Fig. 4 is a view of the fixture attached to a rail of the supporting frame of the table, and

Fig. 5 is a detail view of the fixture in side elevation.

My invention may be applied to any type of table, and for the purpose of illustration I have shown it in connection with a refectory table having a box frame comprising side and end rails 10—11 supported by legs 12

with a center rail 13 on which rests the cross-piece 14a extending between the side rails 10—10 and supporting the top 14 which bears at its ends on the side rails, it being observed by reference to Fig. 3 that the side rails of 55 the supporting frame are cut away beyond the opposite ends of the crosspiece and the end rails 11 similarly cut away to receive the extension leaves 15 in housed position below the opposite ends of the top, and that 60 the extension leaves are carried at the outer ends of bars or runners 16 working in slots 17 and 18 in the end rails and center rail respectively, said runners being of such length as to maintain engagement with the center 65 rail in the extended position of the leaf which it supports. The width of the slots approximate the thickness of the leaf supporting bars or runners and as the latter slide in said slots in the movement of the leaf to extended 70 and housed positions the depth of the slots correspond with the angle of inclination of the supporting bars or runners, in the present instance the under side of each runner having a depression 19 providing for a slight lowering of the outer end of the bar or runner for the engagement of a pin 21 on said bar with the supporting fixture hereinafter described. 75

For supporting the leaves in extended position I provide a metal fixture 21 which is attached to the inner side of the end rail 11 at one side of the slot 17 therein, said fixture having an inwardly projecting member with which the pin 20 on the runner 16 engages for supporting the leaf carried by said runner on a horizontal plane with the top of the table. In the preferred form of this fixture it comprises an attaching plate 22 from one side of which projects a vertical rib 23 extended outwardly at its upper end in the form of an 80 inturned hook 24 the bill 25 of which is spaced from the rib and provides a depression or seat 26 at the inner side of the bill to receive and support the aforesaid pin projecting from the runner carrying the extension leaf. 85 By reference to the drawing it will be noted that the vertical rib on the fixture forms an abutment or stop against which the pin 90 strikes in the limited outward movement of the runner and that the bill of the hook being 95 100

- spaced from said rib leaves an entrance slot for the passage of the pin into engagement with the hook where it is held to prevent horizontal movement of the leaf. The fixtures are attached to the inner side of the end rails 11 by means of screws 27 so that the supporting member of said fixture will be on a line at one side of the slot 17 for engagement of the pin 20 on the runner with said hook.
- 15 The leaves in housed position are supported beneath the projecting opposite ends of the table top in the spaces beyond the ends of the crosspiece 14a on the upper ends of the sides and end rails of the supporting frame of the table, the bars or runners connected to the aforesaid leaves extending through the slots 17 and 18 in the end and center rails, and in the operation of extending the leaves to increase the size of the top of the table each leaf 20 is moved horizontally outward until the pin 20 engages the rib 23 of the metal fixture 21 at which time the said leaf is beyond and slightly below the outer end of the top so that it may be moved upward and rearward for 25 engagement of the pin with the supporting member or hook 24, it being noted that the fixture not only limits the outward movement of the leaf and runner but also serves as a guide in bringing the leaf on a horizontal 30 plane with the main top of the table, and that in this position it is supported and held by the pin resting in the seat 26 of the hook or supporting member and engagement of the runner with the outer end of the crosspiece 14a, as shown in Fig. 2 of the drawing. In housing the extension leaf the operation described is reversed, that is to say the leaf is moved slightly upward to disengage pin 20 from the hook member 24 of the fixture and 40 after being lowered to the position shown in Fig. 3 the said leaf is slid inwardly into the space provided therefor below the projecting ends of the main top, it being noted that the depression 19 at the lower edge of the runner 45 provides the lowering movement of the leaf and runner so that the pin will be below the hook member of the fixture and that said leaf is guided by the runner sliding in the lower ends of the slots 17 and 18 in the cross 50 rails of the supporting frame of the table to the upper edges of the side and end rails over which it slides to housed position.
- 55 The fixture cooperates with the pin to provide a simple and effective means for guiding the runners in raising and lowering the extension leaf as well as to support and hold the leaf on a horizontal plane with the main top, and although in the preferred embodiment of my invention the supporting member 60 is in the form of a hook having the bill portion thereof turned inwardly or toward the end rail it is obvious that the form may be modified to serve the same purpose, that is to limit the outward movement of the leaf 65 and its supporting runner by the pin strik-

ing thereagainst and provide a support for said pin to rest upon, and consequently I do not wish to be understood as limiting my invention to the special form of supporting member herein particularly shown and described but reserve the right to modifications thereof within the spirit and scope of the appended claims.

I claim:

1. In combination with an extension table 75 having a leaf supported by runners slidable in the cross rails of the supporting frame for movement of the leaf from housed to extended position, said runners having a pin projecting laterally therefrom, of a metal fixture attached to the inner side of the end rail for engagement of the pin in guiding the movements of the leaf, said fixture having an inturned supporting member at its upper end with a depressed seat in which the pin rests 80 in positioning and holding the extension leaf on a horizontal plane with the top of the table.

2. In combination with an extension table 85 having a leaf supported by runners slidable in the cross rails of the supporting frame for movement of the leaf from housed to extended position, said runners having a pin projecting laterally therefrom, of a metal fixture attached to the inner side of the end rail for engagement of the pin in guiding the movements of the leaf, said fixture having a vertical guiding member and a supporting member projecting outwardly and inwardly 90 from the upper end thereof with a depression 95 in the upper edge of the inwardly projecting portion in which the pin seats for supporting and holding the extension leaf in abutment 100 with the outer end of the top and on a horizontal plane therewith.

3. In combination with an extension table 105 having a leaf supported by runners slidable in the cross rails of the supporting frame for movement of the leaf from housed to extended position, said runners having a pin projecting laterally therefrom, of a fixture attached to the inner side of the end rail for engagement of the pin in guiding the movements of the leaf, said fixture having a vertical member forming a stop and guide cooperating 110 with the pin, a member projecting from the upper end thereof for guiding the inward movement of the leaf, and a downwardly and inwardly projecting portion at the outer end of said member with a depression in the 115 upper edge of the inwardly projecting portion in which the pin seats for supporting and holding the leaf in abutment with the end of the top and on a horizontal plane therewith.

4. In combination with an extension table 120 having a leaf supported by runners slidable in the cross rails of the supporting frame for movement of the leaf from housed to extended position, said runners having a pin project- 125

ing laterally therefrom, of a metal fixture attached to the inner side of the end rail comprising an attaching plate, a member extending outwardly from the attaching plate, and a downwardly and inwardly projecting portion at the outer end of said member, the inwardly projecting portion having a depression in its upper edge in which the pin seats for supporting and holding the leaf in abutment with the end of the top and on a horizontal plane therewith.

5. A metal fixture for extension tables comprising an attaching plate, a member projecting outwardly therefrom, and a curved portion at the outer end of said member forming a support for a member on a table leaf slide.

6. A metal fixture for extension tables comprising an attaching plate, an outwardly projecting guiding member at the upper end thereof, and a downwardly and inwardly projecting portion at the outer end of said member, the inwardly projecting portion having a depression in its upper edge forming a seat.

7. A metal fixture for extension tables comprising an attaching plate, a vertical rib projecting from said attaching plate to form a vertical guide, an outwardly projecting member at the upper end of said rib, and a downwardly and inwardly projecting portion at the outer end of said member, the inwardly projecting portion having a depressed seat in its upper edge.

8. In an extension table the combination with a top fixed to the side and cross rails of the supporting frame, the upper edges of the side and end rails being cut away to leave spaces below the outer ends of the top, of runners slideable in the cross rails and to the outer ends of which the extension leaf or leaves are attached, said runners having a depression in the lower edge thereof for lowering movement of the extension leaf in its outermost position, and a pin projecting from one side of the runners together with a metal fixture attached to the inner side of the end rail to cooperate with the pin on the runner, said fixture having a horizontal member at its upper end with downwardly and inwardly projecting portions at the outer end of said member, the inwardly projecting portion having a depression in its upper edge in which the pin on the runner engages for supporting and holding the leaf in abutment with the outer edge of the top on a horizontal plane with said top.

9. In an extension table, the combination of a runner carrying the extension leaf, and a rail on the supporting frame having a slot at the bottom of which the runner slides and by which it is guided in the movement of the leaf to extended and housed positions, together with means for supporting the leaf and its runner in position against horizontal displacement comprising a supporting member

attached to one of the aforesaid parts of the table, and a supporting fixture attached to the other of said parts, said fixture having a hook member and an entrance slot leading to the bill of the hook by which the aforesaid member on the companion part of the table passes in the interlocking engagement thereof with the hook.

10. In an extension table, the combination of a runner carrying the extension leaf, and a rail on the supporting frame having a slot at the bottom of which the runner slides and by which it is guided in the movement of the leaf to extended and housed positions, the under side of the runner having a depression for lowering the leaf when in extended position; together with means for supporting the leaf and its runner in position against horizontal displacement comprising a supporting member attached to one of the aforesaid parts of the table, and a supporting fixture attached to the other of said parts, said fixture having a hook member and an entrance slot leading to the bill of the hook by which the aforesaid member on the companion part of the table is guided and interlocked with the fixture against horizontal movement.

11. In combination with an extension table having a leaf supported by runners slideable in a slot in the cross rails of the supporting frame for movement of the leaf from housed to extended position, said runners having a member projecting laterally therefrom, of a metal fixture attached to the end rail at one side of the slot for engagement of the member in supporting the leaf, said fixture consisting of an attaching plate, and a supporting member the upper end of which extends at an angle to the attaching plate and is curved to form a seat for the aforesaid member on the runner supporting the leaf.
